UNITED STATES PATENT OFFICE.

GAËTAN BRUN, OF PARIS, FRANCE.

SELF-PROPELLING CRANE.

1,371,852.

Specification of Letters Patent. Patented Mar. 15, 1921.

Application filed September 30, 1919. Serial No. 327,592.

To all whom it may concern:

Be it known that I, GAËTAN BRUN, a citizen of the Republic of France, and residing at Paris, Seine Department, No. 1 Rue Jules 5 Lefebvre, in the Republic of France, have invented certain new and useful Improvements in Self-Propelling Cranes, (Case B,) of which the following is a specification.

This invention has for its object to provide an improved self-propelling traveling crane so constructed that the motor that propels the vehicle shall likewise be capable of being utilized for operating the crane, that is to say, to slew the crane around on its 15 own axis and to wind up the lifting rope.

An improved apparatus according to this invention is illustrated by way of example in the accompanying drawings in which:

Figures 1 and 1^a are a side elevation partly in section of the entire apparatus.

Fig. 2 is a horizontal section of the lifting winch.

Fig. 3 is a horizontal section showing the lower driving mechanism.

Fig. 4 is a vertical section of the slewing mechanism, and

Fig. 5 is an elevation partly in section of the turn-post.

As shown, the frame A of the improved 30 traveling crane is similar to the frame of a motor lorry but of larger dimensions, since its parts must be designed to withstand the strains to which they will be subjected.

In front of the frame is an engine 1 with 35 a cooling radiator fitted with a fan. The driving shaft is connected to a change speed box 3 through the medium of a clutch 4 and a shaft 2.

This change speed box comprises preferably toothed wheels adapted to give two speeds to the vehicle. From its lower part there issues a shaft 5 driving a rear differential axle 6. This shaft is connected to the change speed box and to the differential 45 back axle by means of Cardan couplings 7 and 8.

The upper part of the box 3 is surmounted by a casting 8^a inclosing a speed-reducing device driving a shaft 9 that transmits the 50 motion to the lifting mechanism.

The front wheels of the vehicle are steering wheels, and the hind wheels E are driving wheels; all these wheels are fitted with single or double rubber tires.

55 Two brakes are arranged on the vehicle, namely, a brake 10 situated at the exit end

of the change speed box, and operated by means of a pedal 11, while the other brake 12 is adapted to act upon the hind wheels and is operated by means of a hand lever 13. 60

In front of the vehicle two seats S S¹ are provided set face to face, and capable of serving simultaneously, one for the driver when controlling the travel of the vehicle, and the other for the driver, or another person when operating the crane. 65

The lifting mechanism consists of an ordinary jib crane provided with a cabin L inclosing the machinery. A fixed portion P situated on the frame A of the vehicle carries the control mechanism F, while a movable portion H B carries the lifting winch K. 70

A turn-post 14 mounted on a ball and socket bearing box 14^a fixed to the frame of the vehicle, carries by means of a yoke 15 75 the revolving platform H, B of the crane.

A shallow dish-shaped plate 16 mounted on the turn-post supports the driving mechanism of the crane.

Bearings 17 (Figs. 1^a and 3) carry shafts 80 18 and 19. The shaft 18 is connected by means of the shaft 9 and Cardan couplings to the speed-reducing device 8^a, and it drives through a pinion 20 a toothed wheel 21 that is loose on the shaft 19. This toothed wheel 85 can be operatively connected to the shaft 19 by means of a clutch 22 preferably of the friction type which is adapted to slide on a feather-key on said shaft. This shaft carries also an automatic lifting brake comprising a pulley 23, a plate 24 and a spring 25. 90

On the turn-post 14 (Fig. 5) there is mounted on balls a hollow shaft 26 carrying a bevel pinion at each end. The lower pinion receives motion from the pinion 27 that 95 is fixed on the shaft 19, and transmits this motion through the upper pinion to the lifting winch.

For driving the slewing mechanism, there is provided on the end of the shaft 18 (Fig. 100 3) a double clutch, preferably of the friction type, comprising a sleeve 28 sliding along a feather-key on the shaft 18. This sleeve allows of throwing into gear one of the two conical pinions 29 and 30 that are 105 loose on the shaft 18, and of driving in one or the other direction a bevel toothed wheel 31 that is fixed on a worm shaft 32.

A pinion 33 (Fig. 4) loose on its shaft 34, 110 can be operatively connected to the latter by means of a claw clutch 35 slidable along a feather-key on said shaft and operated by

a sliding shaft 36, the handle 36^a of which slides over a cam 36^b.

By means of this arrangement the revolving portion is free to revolve around the 5 turn-post 14 so as to allow of operating two apparatuses in series for handling articles of great length.

On the upper end of the shaft 34 there is 10 fixed a pinion 37 for driving a ring of teeth 38 fixed on the revolving crane platform H (Fig. 1^a).

On the end of the worm shaft 32 there is 15 fixed a pulley 39 for braking the sluing motion (Fig. 3).

15 The revolving portion constituting the crane proper, consists of a platform H built up of section bars carrying a cabin L and a pivoted jib M.

20 The platform rests on rollers 39^a, preferably of cast steel, rolling over a circular track O mounted on a floor P fixed on the frame A of the vehicle.

25 The crane platform carries a winch 48 (Fig. 2) comprising a frame 40 surmounted by bearings 41 in which rotate shafts 42, 43 and 44.

30 A bevel toothed wheel 45 fixed on the shaft 42 and actuated by one of the conical pinions fixed to the tube 26, drives through a pinion 46 a toothed wheel 47 that is fixed on the lifting drum 48 carried by a shaft 43.

35 The shaft 44 carries an auxiliary drum 49 on which is wound a rope for raising the jib M. This drum is driven by a toothed wheel 50 meshing with the wheel 47. This wheel 50 is loose on the shaft 44 and can be operatively connected thereto by means of a clutch 51, preferably of the friction type, 40 slidable along a feather-key on the said shaft.

45 A hand brake 52 fitted to the drum 49 serves for regulating the lowering of the jib.

For the sake of security a ratchet wheel 53 is fixed on the drum 49.

45 The raising rope passes over guide pulleys 55 to the pulleys 54 at the head of the jib and to the lifting hook R.

50 The jib is held by tie-rods 56 and can be raised and lowered by the ropes passing from the drum 49 over pulleys 57.

55 It is to be understood that the apparatus is so designed as to enable all the movements to take place simultaneously, that is to say, it is possible at one and the same time to lift the load, to slue the load, and to transport the load, while moreover the crane can rotate indefinitely around its turn-post. On the other hand, the crane driver who is 60 seated on a seat which does not rotate with the crane, remains stationary on the vehicle during the operations.

Claims:

1. A self-propelling traveling crane where-
65 in the engine fixed on the traveling frame

is adapted to serve at the same time to produce the travel of the vehicle and to produce the sluing and lifting movements of a crane mounted on the said frame in such a manner as to be capable of revolving indefinitely 70 around its vertical axis, the seat for the driver of the crane being located on said frame facing the seat of the car driver comprising: a mechanism for producing the lifting and sluing movements comprising a 75 shaft arranged longitudinally on said frame; a speed-reducing device connecting said shaft to the driving shaft; a second longitudinal shaft adapted to be actuated by the first mentioned shaft through the medium of spur wheel gear and a clutch; a vertical shaft arranged in the axis of rotation of the crane, connected to the second longitudinal shaft by a bevel gear; a winch for 80 handling the load; power transmitting 85 means for transmitting to said winch the motion of said vertical shaft; a second vertical shaft; a reversing clutch and a worm gear adapted to transmit the motion of said first longitudinal shaft to said second vertical shaft; and spur gear connecting the latter to the crane platform for producing rotation of the latter.

2. A self-propelling traveling crane where-
in the engine fixed on the frame of the ve- 95 hicle, serves at the same time to effect the travel of the vehicle as well as to produce the sluing and lifting movements of a crane mounted on said frame in such a manner as to be capable of rotating indefinitely 100 around its axis, the seat of the crane driver being located on said frame facing the seat of the car driver, comprising: a me- 105chanism for effecting the lifting and sluing movements comprising a shaft arranged longitudinally on said frame; a speed-re- 110ducing device connecting the said shaft to the driving shaft; a second longitudinal shaft adapted to be actuated by said first shaft through the medium of spur gear and 115 a clutch; a vertical shaft located in the axis of rotation of the crane, connected to said second longitudinal shaft by bevel gear; a winch for handling the load; transmitting means adapted to transmit to said winch the motion of said vertical shaft; a second vertical shaft; a reversing clutch and a worm gear adapted to transmit the motion of said first longitudinal shaft to said second vertical shaft; a spur gear connecting the latter to the crane platform for producing rotation thereof; brakes arranged on said second longitudinal shaft for controlling the lifting, and on the worm shaft for controlling the sluing.

3. A self-propelling traveling crane where-
in the engine fixed on the traveling frame, effects at the same time the travel of said frame and produces the sluing and lifting movements of a crane mounted on said frame 130

in such a manner as to be capable of rotating indefinitely around its vertical axis, the seat of the crane driver being placed on said frame facing the seat of the car driver comprising: a mechanism for producing the lifting and sluing movements comprising a longitudinal shaft located on said frame; a speed-reducing device connecting said shaft to the engine shaft; a second longitudinal shaft adapted to be driven by said first shaft through the medium of a spur gear and a clutch; a vertical shaft located in the axis of rotation of the crane, connected to said second longitudinal shaft by bevel gear; a winch for handling the load; transmitting means adapted to transmit to said winch the motion of said vertical shaft; a second vertical shaft; a reversing clutch and a worm gear for transmitting the motion of said first longitudinal shaft to said second vertical shaft; spur gear connecting the latter to the crane platform for rotating same; and a mechanism adapted to be driven by the engine on said carriage, for raising and lowering the crane jib.

4. In a self-propelling crane, a frame having traction wheels, an engine on said frame, a drive shaft connecting the engine in driv-

ing relation with traction wheels of the frame, crane-operating mechanism and means for connecting said mechanism in driving relation with the engine, comprising a horizontal shaft, a speed-reducing mechanism connecting said shaft in driving relation with the driving shaft, a second horizontal shaft in driving relation with the first-mentioned shaft, a vertical shaft arranged in the axis of rotation of the crane and in driving relation with the said second horizontal shaft, a winch, power-transmitting means for imparting to said winch the motion of said vertical shaft, a second vertical shaft, a clutch and a gear adapted to transmit the motion of said first-mentioned horizontal shaft to said second-mentioned vertical shaft, and a gearing connecting the latter to the crane for producing rotation of the same.

In testimony, that I claim the foregoing as my invention I have signed my name in presence of subscribing witnesses.

GAËTAN BRUN.
